ROTARY DISK SHAVER WITH AXIALLY
MANUALLY FED PUSHER

Archer M. Sampson, Muskegon, Mich.

Application September 13, 1946, Serial No. 696,689

3 Claims. (Cl. 146—61)

1

The present invention relates to shaving devices and more particularly to a device for making soap chips, potato chips and the like.

The primary objects of the instant invention are to provide a device of the general character above indicated which is particularly well adapted for use by the housewife in the making of soap chips and for the making of potato chips and the like; to provide such a device which is highly efficient in its intended use; to provide such a device which is simple in construction; to provide such a device which may be readily and conveniently used; and, to provide such a device which is reasonably economical in manufacture.

An illustrative embodiment of the invention is shown in the accompanying drawing, wherein:

Figure 1 is a perspective view of one part of the device;

Figure 2 is an end elevational view thereof viewed from the left side of Figure 1;

Figure 3 is a top plan view of the complete device;

Figure 4 is a sectional view thereof on line 4—4 of Figure 2 but including the second part of the device; and

Figure 5 is a perspective view showing the separable parts of the device in their non-assembled relation.

Referring then to the drawing wherein like parts of the device shown are designated by the same numerals in the several views, the same comprises a generally formed hollow cylindrical member or casing 10 having an integrally formed peripheral offset portion 11 provided with a receiving mouth or hopper 12 and having an integrally formed internal radial web 13 provided with a tubular axially disposed bearing 14.

A concavo-convex chip discharging hood 15 secured to one end of the generally formed cylindrical casing 10 as by screws 16 is provided with a discharge opening 17 and with an inwardly facing centrally disposed integral tubular bearing 18 in axial alignment with the tubular bearing 14, all as best shown in Figure 4.

A circular cutter disc disposed within one end of the cylindrical casing 10 and having a plurality of radially disposed slits 20—the same side of each slit having a turned portion 21 forming a knife edge—is secured to one end of a pin 22 rotatable within the bearing 18, the outer end of the pin being secured to a crank 23 rotation of which effects the rotation of the disc and its knives.

A second disc 24 having a radial slit 25 is provided with an axially disposed tubular shaft 26

provided with a longitudinal slot 27 in transverse registration with and intersecting the slit 25 of the disc 24 which shaft 26 is adapted to slidably embrace the tubular bearing 14 when the several parts of the device are in their assembled relation, the slit 25 embracing the radial web 13 to prevent rotation of the disc 24 and objects being shaved within the tubular member 10 and the slot 27 permitting its axial movement relative thereto.

The offset portion 11 of the tubular member 10 is here shown as provided with a laterally disposed arm 28 to whose outer end is secured a conventional type fastening member 29 adapting it for detachable connection with a wall fixture.

In use, soap, potatoes or the like to be shaved into chips are inserted within the mouth or hopper 12 of the cylindrical casing 10 between the opposed faces of the circular cutter disk and the movable split disk and whereupon by exerting pressure on the disc 24 through the shaft 26 against the soap or the like within the cylindrical member 10 by one hand and by turning the crank 23 with the other hand, the same is shaved into chips and is discharged through the opening 17.

It will thus be seen that the device herein shown and described is particularly well adapted for use by the housewife in the making of soap chips, potato chips and the like, is highly efficient in its intended use, is simple in construction, may be readily and conveniently used, and is reasonably economical in manufacture.

While but one specific embodiment of the invention has been herein shown and described, it will be understood that certain details of the construction shown may be altered or omitted without departing from the spirit of the invention as the same is defined by the following claims.

40 I claim:

1. A device of the class described comprising a hollow cylindrical casing having a receiving mouth in one wall thereof, a chip discharge cover for one end of the cylindrical casing having a discharge opening, a rotatable disk within one end of the cylindrical casing having radially disposed cutting knives thereon, and an axially movable disk at the end of a tubular shaft within the other end of the cylindrical casing, a fixed bearing centrally disposed within the casing, the tubular shaft being mounted for axial movement on the bearing in the casing, means to prevent relative rotary movement between the tubular shaft and disk and the bearing, and means for rotating the rotatable disk.

2. A device of the class described comprising a hollow cylindrical casing having a receiving mouth in one wall thereof, a concavo-convex chip discharge cover for one end of the cylindrical casing having a discharge opening, a rotatable disk within one end of the cylindrical casing having radially disposed cutting knives thereon, and an axially movable disk of substantially the same size as the rotatable disk at the end of a tubular shaft within the other end of the cylindrical casing, a fixed bearing integral with and centrally disposed within the casing, the tubular shaft being mounted for axial movement on the bearing in the casing, means to prevent relative rotary movement between the tubular shaft and disk and the bearing, and means for rotating the rotatable disk.

3. A device of the class described comprising a hollow cylindrical casing having a receiving mouth in one wall thereof, a chip discharge cover for one end of the cylindrical casing having a discharge opening, a rotatable disk within one end of the cylindrical casing having radially disposed cutting knives thereon, and an axially movable slotted disk of substantially the same size as the rotatable disk integral with the end of a longitu-

dinally slotted tubular shaft within the other end of the cylindrical casing, the slot in the tubular shaft intersecting the slot in the disk, a fixed bearing integral with and centrally disposed within the casing, an upstanding web integral with the bearing and casing and substantially the width of and disposed within the casing, the tubular shaft being mounted for axial movement on the bearing in the casing so that the slot in the disk and the slot in the tubular shaft slides over the web and is thereby prevented from rotation, and means for rotating the shaft and disk.

ARCHER M. SAMPSON.
